UNITED STATES PATENT OFFICE.

ALBERT VOIGT, OF NEW YORK, N. Y.

LOCK.

1,001,100.

Specification of Letters Patent. Patented Aug. 22, 1911.

Application filed November 5, 1910. Serial No. 590,798.

To all whom it may concern:

Be it known that I, ALBERT VOIGT, of the borough of Brooklyn, city and State of New York, have invented a certain new and useful Improvement in Locks, of which the following is a specification.

This invention relates to a simple lock construction embodying as a feature an angularly shiftable spring-actuated catch.

10 With this catch there is combined means for readily locking the catch in its thrown position by a predetermined key while the construction devised permits the lock to be used either upon a swinging or a sliding door.

15 In the drawing accompanying the present specification, Figure 1 is an elevation of a lock embodying the features of my improvement, parts being broken away and the view being such as to show the mortise plate in full width. Fig. 2 is a side elevation looking from the left in Fig. 1, part being broken away. Fig. 3 is an elevation looking from the right in Fig. 1, the casing cover plate being removed. Fig. 4 is a detail perspective, various lock features being removed from their assembled positions. Fig. 5 is a longitudinal section through the key cylinder, the key being in place. Figs. 6, 7 and 8 are sections illustrating various ward 20 combinations. Fig. 9 is a section illustrating the application of the improved lock to a swinging door. Fig. 10 is an elevation, partly in section illustrating the application of the invention to a sliding door.

30 35 Similar characters of reference designate corresponding parts in all figures.

The present lock embraces a spring-actuated catch mounted for angular movement. As here constructed, this feature comprises 40 a bevel-faced catch proper 2 having a stem 3 through which passes a swivel pin 4 entering an opening 5 in the bottom plate 6¹ of the lock casing 6 and an opening 5¹ in the cover plate 6² of the casing. The catch 45 proper is adapted to protrude through opening 7¹ in the mortise plate 7 of the casing, the plate being provided with the usual openings 7² for screws. Cover plate 6² is here provided with slits 8 adapted to engage 50 with lugs 8¹ on the casing rim.

Catch-actuating spring 9 rests at one end against the bottom of a recess 9¹ in the catch body and at the opposite end against a stop 10 rigidly engaged in a slot 10¹ in the casing 55 rim, a spring-centering guide 10² extending from the stop.

The catch is withdrawn from its locking position by means of a rotatable cylinder 11, preferably terminating at one end in a suitable finger piece 11¹. This cylinder passes 60 through an opening 11² in casing plate 6 and has at the remaining end an annular stop-shoulder 11³ carrying a crank pin 12 projecting into a shoulder-forming recess 12¹ in the catch body. 65

Referring now to means for locking the catch against withdrawal as the result of turning the said cylinder, 13 designates a key block mounted and adapted to turn in cylinder 11, its longitudinal movement in 70 one direction in the cylinder being limited by the inturned rim 13¹ of the latter. The slot for the flat key B is designated by 13², this latter alining with notches 13³, 13⁴ in rim 13¹ to permit the insertion and withdrawal of the key in the locked and the unlocked condition of the catch. The block is 75 reduced in diameter at one end, see 14, to expose the edge of the inserted key and is provided with key-steadying wings 14¹, 14² 80 at the sides of the key slot.

A ward 15 projects from a lever 15¹, here conveniently mounted upon the swivel pin 4 in a slot 15² in the stem 3 of the catch and pressed by a spring 15⁴ toward the key 85 block. The number of these wards and ward levers, as well as their relation to washers 16 on pin 4 may be variously changed in order that a key with a particular number and arrangement of ward 90 notches shall be necessary to operate any given lock. Thus, in Fig. 6 two such levers and three washers are indicated, in Fig. 7, three wards and two washers, while in Fig. 8 a still different combination is represented. The key block may have a shoulder-forming projection 17 adapted to strike 95 against the wards and limit the turning movement of the block.

A locking eccentric 18 fits over the reduced portion of the key block, it being keyed thereto by the aforesaid wings 14¹, 14² which enter notches 19, 19 in the eccentric. When the block is in the unlocked condition, the catch is free to be withdrawn 100 but when the block is turned to the locked position, the eccentric impinges against 3 of the catch and holds the latter against withdrawal.

105 The catch plate is designated 20. By reason of the fact that the catch proper is beveled, the catch impinging

against the striking edge of the catch plate is readily forced in, simultaneously turning about its axis against the resistance of its spring 9, and snaps into the catch opening thus adapting the device for use with a swinging door. Furthermore, the same result of overcoming the spring tension arises when the lock is applied to a sliding door and since the catch proper is undercut, see 10 Figs. 2 and 3, and it has snapped into the catch opening, the door can not be slid back until the catch is manually turned, see Fig. 10.

Preferably, when used on a sliding door 15 there is secured to plate 7 of the lock casing a positioning dowel 21 adapted to enter a corresponding opening 22 in the catch plate and aline the locked parts.

Having described my invention, I claim;—
20 1. In a lock, the combination of a casing, a swiveled spring-pressed catch, a cylinder having a crank pin connection with said catch, a key block mounted in said cylinder concentrically therewith, and a locking piece carried by said block and adapted to coöperate with said catch.

2. In a lock, the combination of a casing, a swivel pin in the casing, a spring-pressed catch mounted on the pin, a cylinder mounted 30 in the casing and having a crank pin connection with said catch, a key block mounted in said cylinder, spring pressed ward levers, and a locking eccentric secured to said key block.

3. A lock embodying in combination, a 35 casing, a swiveled spring-pressed catch having a beveled and undercut face as described, a swivel pin in the casing to which said catch is swiveled, a cylinder mounted in said casing and having a crank pin connection with said catch, a key block mounted in said cylinder, spring pressed ward levers, a locking eccentric secured to said key block, and means for securing a centering pin to said casing. 40 45

4. A lock embodying in combination, a casing, a swiveled spring-pressed catch having a beveled and undercut face as described, a swivel pin in the casing to which 50 said catch is swiveled, a cylinder mounted in said casing and having a crank pin connection with said catch, a key block mounted in said cylinder concentrically therewith, said cylinder being provided with a finger piece and a stop shoulder at one end and 55 an inturned rim at the other end overlying said block, spring pressed ward levers mounted on said swivel pin, a locking eccentric secured to said key block, and means for securing a centering pin to said casing. 60

In testimony whereof, I have hereunto signed my name in the presence of two subscribing witnesses.

ALBERT VOIGT.
